UNITED STATES PATENT OFFICE.

HARRY W. SIEMUND, OF CHICAGO, ILLINOIS.

PENCIL.

Application filed September 12, 1921. Serial No. 500,068.

To all whom it may concern:

Be it known that I, HARRY W. SIEMUND, a citizen of the United States, and a resident of Chicago, in the county of Cook and State of Illinois, have invented a new and useful Improvement in Pencils, of which the following is a full, clear, and exact description.

My invention relates to pencil of that type of construction in which a plurality of pieces of lead are held in reserve, and it consists in the combinations, constructions and arrangements herein described and claimed.

An object of my invention is to provide a magazine pencil adapted to hold a plurality of pieces of lead, each of which can be moved into position for use without being grasped by hand.

A further object of my invention is to provide a pencil of the character described having means for indicating the particular lead in position for use at a given time.

A further object of my invention is to provide a device of the character described in which means are provided for releasably holding a selected piece of lead in position for use.

A further object of my invention is to provide a device of the character described that is simple in construction, not likely to get out of order easily and thoroughly practical commercially.

Other objects and advantages will appear in the following specification, and the novel features of the invention will be more particularly pointed out in the appended claims.

My invention is illustrated in the accompanying drawings forming part of this application, in which—

Figure 1 is a side elevation of a pencil embodying my invention,

Figure 2 is an enlarged central section through the pencil along the line 2—2 of Figure 3,

Figure 3 is a section along the line 3—3 of Figure 2,

Figure 4 is an elevation of a fragmentary portion of the device,

Figure 5 is an end view of a portion of the device shown in Figure 4, and

Figure 6 is an enlarged elevation of another fragmentary portion of the pencil.

In carrying out my invention, I provide

a cylindrical body 1 that is conventional in form and is tapered at its lower end as indicated at 2. The body 1 is fashioned with an axial bore 3 extending the entire length thereof. This bore is formed for part of its length to provide a plurality of radially disposed chambers 4, each of which extends longitudinally of the bore and is in open communication therewith, as clearly shown in the drawings. The body 1 is threaded interiorly below the lower ends of the chambers 4, as at 5 for engagement with threads 6 of a lead holding barrel or sleeve 7 which is arranged to extend the entire length of the body and to protrude above the upper end thereof, the protruding portion 8 being relatively large diametrically. The barrel 7 is provided with a slot 9 through its wall extending longitudinally thereof from the lower end of the enlarged portion 8 to the lower end of the chambers 4. The slot 9 has a width equal to the distance between opposite walls of each chamber 4 at the points of juncture of the latter with the bore 3.

The barrel 7 is open at both the upper and lower ends thereof and is formed with a plurality of slits 10 extending longitudinally from the lower end thereof for a short distance, thereby defining a plurality of gripping fingers 11. The latter will be moved inwardly when the barrel 7 is turned within the bore of the body 1 to occasion an axial movement of the barrel along a tapering lower portion of the bore toward the lower end of the body. A piece of lead 12 disposed within the barrel 7 and arranged to depend below the lower end thereof will thereby be gripped by the fingers 11 and held in adjusted position.

The body 1 is formed with an annular rib 13 adjacent to its upper end and a ring 14 revoluble on the body is maintained thereon by the engagement of this rib with an annular groove 15 in the inner wall of the ring. The ring 14 extends beyond the upper end of the body 1 and the upper end thereof is received within an annular groove 16 in the lower end of an adjusting cap 17. The latter has a threaded central socket 18 adapted to receive the enlarged portion 8 of the barrel 7 which is screw threaded for engagement therewith. The cap 17 has marked thereon an arrow 19 and is adjusted on the barrel 7 so that

the arrow 19 indicates the position of the slot 9.

From the foregoing description of the various parts of the device, the operation 5 thereof may be readily understood. A piece of supply lead may be placed in each of the chambers 4. The body 1 is marked adjacent to the ring 14 with suitable characters to indicate the location of the several chambers 4, and if desired, to indicate the character of the supply lead that is to be placed 10 in each chamber. The ring 14 is provided with an index arrow 20. The body 1 is grasped in one hand and the cap 17 is then 15 turned until the slot 9 of the lead holding barrel 7 has been moved into registry with the opening of the chamber containing the selected lead. The body 1 is then tilted from a vertical position and turned so that the selected 20 chamber will be uppermost, whereupon the selected lead will fall into the bore of the barrel 7. When the body 1 is then held perpendicular, the selected lead will 25 slidably move in the bore of the barrel 7 until the lower end thereof protrudes below the end of the barrel. The length of the protruding portion of the lead is then adjusted as desired and the cap 17 is then 30 turned relatively to the body portion to cause the gripping fingers 11 to engage the selected lead, whereby the latter will be held firmly in position for use. It is to be observed at this point that the ring 14 is rotated until the arrow 20 indicates the 35 chamber from which the lead is transferred into the barrel 7. This is done prior to the transfer of the lead. Consequently, the arrow 20 will indicate the position of the slot 9 as well as the position of the empty chamber 40 at the time the lead is moved into position in the barrel 7 in the manner described and before the cap 17 has been turned relatively to the body 1 to cause the lead in the barrel to be gripped. The lead in the barrel 7 may 45 be returned to the empty chamber at will and the several pieces of supply lead may be used selectively.

The pencil is particularly well adapted for use by artists and draftsmen who have 50 frequent occasion to use leads of varying degrees of hardness.

It will be observed that the body 1 in the form of device illustrated is formed of two axially aligned connected sections, one of 55 which constitutes a tip enlarged inwardly at its extremity, as shown.

I claim:

1. A pencil comprising a cylindrical body tapered at one end and provided with a central bore having a plurality of chambers 60 formed in its wall to extend longitudinally thereof from its upper end for part of its length and being threaded interiorly below the lower ends of the chamber, and a lead holding barrel having a slot through its 65 walls extending longitudinally thereof for a distance approximately equal to the length of said chambers, said barrel being threaded exteriorly for part of its length for engagement with the bore of said body and being 70 provided with gripping fingers at its lower end, whereby the fingers are moved into engagement with a lead disposed in the barrel when the latter is turned to occasion a movement thereof axially toward the lower end 75 of the body.

2. A pencil of the character described comprising a cylindrical body tapered at one end and provided with a central bore therethrough having a plurality of radially disposed chambers formed in its wall to extend longitudinally for part of its length, said body member being provided with an annular flange on its outer wall adjacent the upper end thereof, a sleeve fashioned 80 with an annular groove on its inner wall adjacent the lower end thereof and arranged to rotatably engage with the flange on said body member, a cap secured to said sleeve at the upper end thereof, a lead holding barrel having a slot through its walls extending longitudinally thereof for a distance approximately equal to the length of said 85 chambers, and means associated with said lead holding barrel for gripping the lead 90 contained therein, said barrel being arranged to move into registration with said chambers selectively by rotation of said cap.

3. In a pencil of the character described, a body member tapered at one end and provided with a central bore therethrough, said body member having an annular outwardly extending flange on its outer wall adjacent the upper end thereof, a sleeve having an annular groove on its inner wall adjacent 105 the lower end thereof rotatably mounted on the flange of said body member, a cap fixed to the upper end of said sleeve, and a lead holding barrel secured to said cap at its upper end and disposed in the central bore 110 in said body member.

HARRY W. SIEMUND.
